BY Frank B. Howell
Conrad Abteneck
his ATTORNEY.

UNITED STATES PATENT OFFICE.

FRANK B. HOWELL, OF BUFFALO, NEW YORK.

DESIGN FOR A HEATING APPARATUS.

60,096.

Specification for Design.

Patented Dec. 27, 1921.

Application filed December 23, 1920. Serial No. 432,866. Term of patent 14 years.

To all whom it may concern:

Be it known that I, FRANK B. HOWELL, a citizen of the United States, residing at the city of Buffalo, Erie county, in the State of New York, have invented a new, original, and ornamental Design for a Heating Apparatus, of which the following is a specification, references being had to the accompanying drawing, forming part thereof.

In said drawing;

Figure 1 is a front elevation showing a

heating apparatus embodying or incorporating my said design;

Fig. 2 is a left end elevation, and

Fig. 3 is a right end elevation of the same.
I claim—

The ornamental design for a heating apparatus, as shown.

FRANK B. HOWELL.
